BUFFING TOOL FOR SHOE SHANKS
AND SOLESPiacentino Lauretti, Carlisle, Pa., assignor to
Charles A. Wardecker, Carlisle, Pa.

Application April 27, 1935, Serial No. 18,643

11 Claims. (Cl. 51—197)

This invention relates to buffers used in the finishing of shoes, and particularly to a buffer designed for use in buffing and polishing the shanks and soles of fine shoes.

In order to bear against and buff the delicate curves of the under face of a shoe shank and of a sole, it is necessary that the buffer should be yielding but firm, and that the sandpaper or emery cloth constituting the face of the buffer should be stretched tightly over the face of the buffer when in use.

The general object of my invention, therefore, is to provide a buffer of this character, which comprises, generally speaking, a mushroom-shaped pad of rubber, a concavo-convex sheet of emery cloth adapted to fit over the outer concave face of the pad or core, means for holding the sheet upon the core or pad, and means for supporting the core or pad upon a rotating shaft.

A further object is to provide a buffer which will be radially flexible as well as circumferentially flexible and in which the centrifugal force generated by the rapid rotation of the buffer and its shaft will act to urge the margin of the buffer outward or flatten it slightly and thus tighten up on the emery cloth, this expansion of the buffer under centrifugal force rendering it particularly soft and yielding when applied to the shoe, and particularly adapted to fit the delicate curves of the shank and sole of a shoe.

My invention is illustrated in the accompanying drawing wherein:

Figure 1 is a sectional view through a buffer constructed according to my invention, the shaft being stationary;

Figure 2 is a like view to Figure 1 but showing the manner in which the centrifugal action of the shaft urges the margin of the core outward against the emery cloth;

Figure 3 is an inside plan view of the core and the cloth layer thereof before the clamping plate has been put in place;

Figure 4 is a perspective view of a modified form of core.

Referring to the drawing, 10 designates a pad or core of soft rubber having a generally concavo-convex form and having a central protuberance or hub 11. This protuberance 11 is hollow, as at 12, and there is a central opening 13 leading through the inner wall of this hub 11 and opening into the space 12. For supporting this core or pad upon the shaft 14, I provide a head 15 having a screw threaded shank 16 which extends into a screw threaded bore in the shaft 14. This head 15 is shown as being conical in shape. I do not wish to be limited to this exact construction as the hub 11 might be of other forms and the head 15 cast within the hub. With the construction illustrated, however, it is possible to insert the pointed end of the head 12

through the opening 13 and thus force the head into the core.

Associated with the mushroom-shaped core is a sheet of sandpaper, emery paper or like material. Hereafter I shall refer to this sheet as being of emery cloth, but it is to be understood that any equivalent material of this character may be used. This sheet of emery cloth is molded so that it approximately fits the outer surface of the core 10 and extends down to the peripheral edge of this core. Thus, the sheet 17 of emery cloth is preferably, as before stated, concavo-convex before it is applied. This covering 17 of emery cloth is provided at a plurality of points with radial tabs 18 formed with apertures 19 adapted to be slipped over the shank 16 of the head 15. In other words, these tabs are brought around the peripheral edge of the core and engaged with this shank.

For the purpose of holding the emery cloth in place securely and exerting a tension upon the tabs, I provide a metallic plate 20 having a somewhat dished-form, that is, provided with the inwardly projecting marginal flange 21, the center of this plate being apertured for the passage of the screw threaded shank 16. When the emery cloth has been disposed over the face of the core 10 with the shank passing through the apertures of the tabs, then the tensioning plate 20 is put in place and then the shank is screwed into the bore of the shaft 14. This presses the plate 20 inward, tightening up on the tabs and drawing inward on the margins of the tabs. In Figure 4, I have illustrated the fact that the core 10 outward of the central hub 11 may be radially slit, as at 22. This is for the purpose of securing extreme flexibility for the outer portion of the core, these slits 22 extending inward through the skirt of the concavo-convex core 40

nearly or entirely to the central hub. When the buffer is at rest, the emery cloth will not fit closely against the flexible margin of the core but as the buffer is rotated at a high speed by the shaft 14, centrifugal force will tend to urge the flexible marginal portion of the core outward, thus slightly flattening the core and placing such a strain upon the emery cloth that the margin of the buffer will fit tightly against the inner face of the emery cloth, thus holding 50 the emery cloth against any tendency to wrinkle. By reason of the fact that the marginal portion of the core and the marginal portion of the emery cloth are forced outward by centrifugal force, an extremely yielding concavo-convex buffer is provided which is sufficiently yielding to fit and take the curvature of any portion of the shoe to which it can be applied and yet which forms a firm support for the emery cloth and provides for a yielding pressure being exerted 60

upon the emery cloth as it is applied to the face of the shank or sole of the shoe.

While I have shown the emery cloth as being pre-formed to have a concavo-convex shape to thus fit approximately closely to the convex face of the core, I do not wish to be limited to this as the layer of emery cloth might be otherwise formed and caused to fit against this convex face by tension of the parts when the emery cloth is 10 put in place.

I have found that a buffer of this character is particularly effective in giving a delicate buffing to those parts of a shoe which have delicate curves and surfaces which might be marred by 15 a workman using a buffer whose core was relatively rigid. The parts of the shoe referred to require buffing on a buffing wheel having a convex face but if the core is made as a solid core without the flexible margin shown in my drawing, 20 there will not be a sufficient yielding of the core to prevent too great a buffing and a consequent marring of the surface if the workman does not take particular care. It will be seen that the margin of this buffer is capable of flexing radially 25 as well as circumferentially and thus it will follow the curvature of a member being buffed without cutting through or grinding through the face of the member as it would do if rigid.

While I have heretofore referred to the core 30 as being of soft rubber, I wish it distinctly understood that it might be formed of other materials such as leather or felt. Preferably, however, it will be of soft rubber as this has an elasticity which will bring it back to its original shape after 35 the shaft has stopped rotating.

What is claimed is:—

1. A buffer of the character described, including a concavo-convex core of yielding elastic material having its marginal portion free to flex 40 circumferentially and radially, means for mounting the core upon a shaft, and means for holding an outer covering of emery cloth upon the core.

2. A buffer of the character described, including a concavo-convex core of soft rubber having 45 its marginal portion entirely free to flex circumferentially and radially and having a solid centrally disposed hub portion, means for mounting the core upon a shaft, and means for holding an outer covering of emery cloth upon the core.

3. A buffer of the character described, including a concavo-convex core of soft rubber having a central hub portion on its concave face, that portion exteriorly of the core being free to flex 55 a screw threaded shank projecting from this hub portion whereby the core may be mounted upon a shaft for rotation therewith, and means for holding an outer covering of emery cloth upon the outer convex face of the core.

4. A buffer of the character described, including a concavo-convex core of soft rubber having its marginal portion free to expand under centrifugal force and flex inwardly under pressure, means for mounting the core upon a shaft, 60 and means for holding an outer covering of emery cloth upon the convex face of the core.

5. A buffer of the character described, including a concavo-convex core of soft rubber having a central hub upon its concave face, the marginal 70 portion of the core from the central hub to its periphery being free for flexing movement, the marginal portion of the core being radially slotted,

means for mounting the core upon a shaft for rotation therewith, and means for holding an outer covering of emery cloth upon the core.

6. A buffer of the character described, including a concavo-convex core of soft rubber having 5 a central hub upon its concave face and having its marginal portion free to expand under centrifugal force and be flexed inward under pressure, a screw threaded shank projecting from the inside end of the hub, a concavo-convex layer of 10 emery cloth approximately fitting the convex face of the core and having radial tabs adapted to be extended inward and each apertured for the passage of the shank, a shaft upon which the shank is mounted, and a plate adapted to be 15 disposed between the end of the shaft and the inwardly turned tabs to bear against said tabs to hold the cloth upon the core.

7. A buffer of the character described, including a concavo-convex core of soft rubber having 20 a central hub upon its concave face and having its marginal portion free to expand under centrifugal force, a screw threaded shank projecting from the inside end of the hub, a concavo-convex layer of emery cloth approximately fitting the 25 convex face of the core and having radial tabs adapted to be extended inward and apertured for the passage of the shank, a shaft upon which the shank is mounted, and a plate adapted to be disposed between the end of the shaft and the 30 inwardly turned tabs to bear against said tabs to hold the cloth upon the core, the margin of the plate having a flange engageable with the tabs to tighten them as the shank is turned inward on the shaft.

8. A buffer of the character described, including a concavo-convex core of soft and yielding material, having its marginal portion free to flex circumferentially and radially and having a central hub on its concave face, a shank extending inward from the hub and adapted to be engaged with the shaft for rotation therewith, and means for holding an outer covering of polishing material upon the core.

9. A buffer of the character described, including a concavo-convex member of soft and yielding material having a central hub upon its concave face and having its marginal portion exteriorly of the hub free to flex circumferentially and radially, and a screw threaded shank extending inward from the hub whereby the member may be mounted upon a shaft.

10. A buffer of the character described, including a concavo-convex body of soft and yielding material having a central hub upon its concave 55 face and having a marginal portion outward of the hub free to flex circumferentially and radially, said marginal portion being provided with radial slits, and a shank extending inward from the hub whereby the buffer may be mounted upon 60 a shaft.

11. As a covering element for buffers having a core provided with a convex face, a circular sheet of material having a polishing face, the sheet being concavo-convex with its polishing face constituting the outer face of the sheet, said sheet having radial tabs, each tab having a perforation, the tabs being adapted to extend inward and overlie each other with their perforations in register.

PIACENTINO LAURETTI.
